UNITED STATES PATENT OFFICE

ISAAC W. LITCHFIELD, OF BOSTON, MASSACHUSETTS, ASSIGNOR TO BEMIS INDUSTRIES INC., OF BOSTON, MASSACHUSETTS, A CORPORATION OF DELAWARE

CONCRETE FORM

Application filed November 25, 1927. Serial No. 235,439.

This invention relates to a form designed to receive poured concrete for the construction of concrete walls, partitions, foundations, and the like.

5 This form comprises standardized members which are adapted to be rapidly and easily assembled and to be quickly removed from the concrete after the same has set. The form is self-supporting and does not 10 necessitate the driving of uprights or stakes into the ground nor the use of auxiliary braces.

The type of structure disclosed herein is adapted to be assembled of standardized 15 parts which are preferably dimensioned according to a modular system, although the size of the parts obviously may be varied to suit individual requirements. With the exception of small inexpensive metal tie members and standard threaded nuts, all of the parts of the form may be used over and over again, it only being necessary to replace these tie members and nuts which remain embedded in the concrete wall.

25 One advantageous aspect of the invention relates to the ease with which the mold boards may be moved upwardly or removed entirely as the concrete adjoining the lower part of the wall takes its initial set in order to permit 30 facing of the green concrete while it is somewhat soft and easy stripping of the mold boards from the face of the concrete. Connecting members and ties for this form may be easily adjusted to the most desirable 35 height in order to permit effective bracing for the form under the particular conditions for which it is being used.

The above and further advantageous features of the invention will be apparent to 40 those skilled in the art upon a reading of the subjoined description and claims in conjunction with the accompanying drawings, in which:

Fig. 1 is a broken side elevational view of 45 a concrete form exemplifying the preferred embodiment of the invention;

Fig. 2 is a section on line 2—2 of Fig. 1;

Fig. 3 is a section on line 3—3 of Fig. 1, parts being broken away;

50 Fig. 4 is a detailed elevational view of an

adjustable brace which permits variation in the width of the form;

Fig. 5 is a detail view partly in section and partly in elevation of part of the assembly shown in Fig. 4;

Fig. 6 is an elevational view corresponding to Fig. 4 but showing an embodiment of the invention wherein the sides of the form are at a fixed distance;

Fig. 7 is a horizontal section through the 60 form construction used at the corner of a wall, partition or foundation;

Fig. 8 is a similar view of another type of corner construction;

Fig. 9 is a detailed elevational view of the 65 fastening means for a tie;

Fig. 10 is a similar view of another type of fastening means;

Fig. 11 is a section on line 11—11 of Fig. 9;

Fig. 12 is a broken elevational view of a 70 portion of a form construction;

Fig. 13 is a detail view, partly in elevation and partly in section;

Fig. 14 is a similar view of a corner 75 assembly;

Fig. 15 is an elevational view of a bracket which is shown in Fig. 13;

Fig. 16 is a sectional view of the cam mounting;

Fig. 17 is a detail view of an attachment 80 for varying the effective length of the lower ties;

Fig. 18 is a sectional view of the corner of the wall assembly; and

Fig. 19 is an elevational view of a corner 85 assembly.

A concrete form of the type illustrated in the accompanying drawings comprises pairs of metal uprights 1 which preferably are of I-cross-section. These uprights are spaced 90 apart at such a distance that their inner faces substantially define the width of the wall that is to be poured within the form. In order to hold the uprights 1 in position upon the ground or upon the foundation 95 where the wall is to be poured, I provide a series of longitudinal tie members 2. Preferably the bases of the members 1 are provided with outstanding ears 3 which have openings to receive the down-turned ends 4 of ties 2 100

which may be formed of wire of fairly heavy cross section. In order accurately to determine the position of the lower ends of uprights 1, I provide the metal ties 7, Fig. 3. These ties preferably are provided with upturned end portions 8 which may terminate in the inturned extremity 9. An opening is provided in each of the end portions 8 to receive a suitable fastening bolt 10, while the arrangement of the flange 9 and the body portion of the tie prevents the fastening nut 11 from turning on the bolt when the upright is secured to the end of the tie. Preferably the mid portion of the tie is provided with a small opening 12 which is extremely useful in centering the form and locating the I-beams in accurate longitudinal alignment.

The upper ends of uprights 1 are connected by the transverse braces 20. These members preferably are of metal and are provided with end portions 21 extending at right angles to the body portion of the member 20 and adapted slidably to engage the outer faces of the I-members. The extremities of the member 20 may be inturned, as designated by numeral 22, to provide lugs engaging edges of the outer flanges of the uprights so that the end portions of the member 20 are adapted in effect to enclose the I-beam and to be slidably mounted thereon.

In order to maintain the member 20 in fixed position upon the I-beams upon which it is mounted, I provide the cam-like locking members 25. These members are pivotally secured by bolts 26 to the intermediate portion of the member 20 and have curved faces 28 which are adapted to be forced against the inner faces of members 1, thus firmly gripping these members between the locking elements and the end portions 21 of members 20. The members 25 may be brought into and out of locking position by tapping them with a hammer or similar implement. Projecting outwardly from each of the members 21 are the ears 29 which are provided with openings 30 to receive the down-turned end portions 31 of longitudinal ties 32. Thus means are provided properly to space and position the ends of the I-members transversely and longitudinally in order to compose a self-supporting framework therewith.

Ofttimes it is desirable to provide a form of this character which may be utilized for the pouring of walls of various standardized dimensions, for example, 8, 10, or 12 inches. For this purpose I provide transverse braces similar to the members 20 but permitting the adjustment of the form to different widths. Figs. 4 and 5 illustrate in detail such a type of construction, it being understood that the lower ties 7 may be provided in various standardized lengths to correspond to the various adjustable widths of the upper transverse connecting members. Referring particularly to Figs. 4 and 5 of the drawings, the uprights

1 are of the character previously described and one end of the transverse brace 40 is provided with an end portion 21 and flange 22 like that of member 20. The other end of member 40, however, extends outwardly in a substantially straight direction and receives the adjustable bracket 42 which is slidably mounted thereon and which is adapted to be disposed in one of several selected positions.

One end of this bracket is provided with shoulder portions 43 which engage marginal portions of one face of the brace, and its other end is provided with a connecting member 45 which is adapted to engage the opposite face of the member 40 and which carries a projection 46 adapted to fit within one of a series of openings 47 in member 40. The shoulders 43 are formed upon the outstanding portion 44 of the bracket which is provided with a face 49 to engage the outer face of one of the uprights 1. When the bracket 42 is not engaged against the member 1, it is adapted loosely to slide along the body portion of the cross brace, the relative position of parts 43 and 45 permitting the removal of the nub 46 from opening 47, as indicated in the dot and dash lines. When the outstanding portion 44 of the bracket is brought into abutting engagement with the outer face of the upright, the portion 45 is pressed inward against the member 40 and the projection 46 is held in interfitting engagement with opening 47, movement of the member 25 to locking position serving to retain the bracket in firm engagement with the upright, as shown in Figs. 4 and 5. Cam-like locking members 25 are provided firmly to hold the upper ends of the I-members 1 against the end portion 21 of brace 40 and against bracket 42, it being evident that a plurality of openings are provided to receive the bolt 26 for the locking member adjoining the adjustable bracket; thus, when the form is adjusted to its position of maximum width, the bolt 26' may be located in an opening which is adapted to receive the locking projection 46 upon bracket 42 when the form is adjusted to one of its narrower positions.

Form boards 50 are adapted to be located with their ends slidably mounted in the channels formed between the flanges of I-members 1, as shown. Preferably the vertical corner of the form board which engages this flange is cut away, as designated by numeral 51. In order to hold the form boards in firm position in relation to the uprights 1, I provide locking members 53 which are pivotally mounted upon the bolts 54 that pass through the form boards. These locking members are provided with wedge-like ends 55 which are adapted to be forced into engagement with the flanges of the I-beam in order rigidly to hold the form boards in position, it being evident that the locking members can be moved into and out of operative position 1.

5 by tapping with a hammer or similar tool. It is further evident that the form boards are separate and distinct from the locking means for the framework of the concrete form so that their movement to different vertical positions in relation to the form does not necessitate any change in the self-supporting framework of the form itself but merely loosening and tightening of the members 53.

10 Fig. 7 illustrates one type of form construction used where the corner of a wall, foundation, or the like is to be poured within the form. The uprights 1, tie members 7, etc. are erected adjoining the corner in the usual 15 manner, but the form boards at the corner are of special form and are designated by numerals 60 and 61 respectively. These form boards preferably have ends cut away, as designated by numeral 51, in order to engage the 20 flanges of the I-beams but have their adjoining ends rabbeted, as designated by numeral 62, in order to permit their interfitting engagement at the inner and outer corners of the proposed wall. The form boards 60, 61 25 are each provided with locking members 53 similar to those previously described for securing the mold boards to the I-beams. At the inner corner of the form a suitable diagonal tie 64 is provided to connect ears 3 upon 30 the I-members, a similar member being provided to connect the ears 29 at the upper ends of the I-members, if desired. At the outer corner of the form I preferably provide an upright angle member 66 to hold the rabbeted 35 portions of form boards 60 in firm interfitting engagement. Preferably the tie 67 is adapted to extend about the angle member 66 connecting the ears upon the I-beams at the outer faces of the wall in the manner shown.

40 Fig. 8 shows another form of corner construction in which short mold boards or form boards 70 define the outer faces of the corner section of the proposed wall, these mold boards having both ends received in I-members 1 in the conventional manner. At the 45 outer corner of the wall, however, these I-uprights 1 are arranged so that their inner faces define the corner of the wall to be poured. Between the webs of these members 50 1, I arrange certain corner pieces 72 which may be of angular metal castings. Preferably the members 1 at this portion of the construction may be drilled, as designated by numeral 73, in order to receive screws 74 with 55 countersunk heads, which secure them to the members 72. Short diagonal ties 75' may connect the ears at the outer sides of these I-beams. I preferably provide a filler piece 75 which may be bolted to the web of one of the I-beams in order accurately to define the inner face of the wall to be poured. If desired, I may provide the short wire connections or ties 79 to extend diagonally between the ears upon the inner corner of the form.

60 Figs. 9 and 11 show one manner of se-

curing the tie members firmly in place upon the ears of the I-members or of the braces 20, the numeral 3 designating in general one of these ears with an opening 80 therein of somewhat larger diameter than the diameter of the tie 82. The down-turned end portion 70 84 of the tie is adapted to be received in the opening 80 and is provided with a flanged over extremity 85 which defines a recess or groove 86 to be pressed into interlocking engagement with one edge of the opening 80. The flattened wedge-like member 87, which may be a suitably shaped nail or brad, is designed to be driven between the down-turned portion 84 and the opposite side wall of opening 80 in order to effect this interlocking engagement. Fig. 10 illustrates a similar construction in which the end portions 84 of the tie 82 are offset from the body portion thereof, as designated by numeral 89.

75 It is evident that a concrete form of this character is adapted rapidly to be assembled of standardized units in order to permit the pouring of concrete walls, foundations, or partitions and that it may be quickly assembled and disassembled in order to permit its use in other locations. A concrete form of this character may preferably be erected by first locating the braces 20 adjoining the ends of pairs of I-members 1, it being understood 80 that the position of these braces may be varied to suit the particular uses of the form to be erected, and that, if desired, more than one set of members 20 may be used for each set of uprights; thus there might be more than two longitudinal tie members between the uprights 1. The ties 7 may then be bolted to the base portions of the uprights 7. The pairs of uprights, as thus secured together by members 7 and 20, may then be moved to a 85 vertical position, and their lower ends be secured together by the longitudinal tie members 2, while the ties 32 are engaged with ears 29 in order accurately to determine the longitudinal placing and positioning of the 90 pairs of uprights.

95 In Fig. 12 the I-members 101 and form boards 50 correspond in general to those illustrated in Fig. 1. The cams 153 correspond to cams 53 but differ therefrom in detail as will 100 be described below. The longitudinal ties 102 adjoining the lower portion of this form merely comprise bar elements having hooked ends that are adapted to be entered in notches 105 103 of I-members 101 and then dropped into 110 place as shown in Fig. 12.

115 The upper longitudinal connecting factors for this form comprise rangers 132 which are preferably angle members having notches 133 upon their lower margins spaced 120 at modular distances and adapted to engage brackets connected to the uprights. These 125 brackets are designated in general by numeral 150 and are each provided with an up-standing portion 151 having an opening 152 130

to receive a fastening 143 to secure them to the transverse connections 120 which in general correspond to the connecting members 20 of Figs. 1, 2, etc. A suitable protuberance 155 is spaced from upstanding portion 151 of the bracket to engage or substantially to engage the opposite face of brace 120. An upstanding portion 156 of the bracket is spaced from the upright portion 151 in order 10 to receive the leg of the ranger or longitudinal connecting member 132. A suitable nub or protuberance 157 is provided in this channel to interlock with one of the notches 133, while an opening 145 receives a nail or the like 146 to prevent the accidental lifting of the ranger. It is thus evident that the brackets may be more or less permanently secured to the transverse braces 120 and that they are readily interlocked with the rangers 132 in order to secure the uprights at any desired modular distance from each other.

A suitable protuberance 161 may be provided to hold the brace 120 at a suitable height.

25 At the outer corner portion of the form I may provide a series of brackets 72, such as shown in Fig. 14, to secure I-members 101 in place. I preferably provide brackets 160 to engage the rangers at this portion of the assembly. Each of these brackets is preferably bolted to the upright by fastening elements 162, Fig. 12, and is provided with an upstanding finger 165 which is adapted to engage the depending leg of angle member 132. 30 35 A suitable protuberance 168 is adapted to engage a notch 133 in the ranger in order to hold these members in desired relation to each other.

In the form of the invention shown in Fig. 12 the cam members preferably are located upon plates 170 which are screwed to form boards 50. The plates are provided with outstanding studs 171 having ears 172 which are bent down into loose engagement with the outer faces of the cams, thus holding them pivotally mounted upon form board 50. The cams may be lightened by openings 178, if desired.

The use of standard hot rolled I-beams results in the provision of a flange of tapered cross section, thereby permitting the use of a cam member having a tapered end portion which is adapted to engage the flange of the I-beam with a wedge-like action and providing a greater frictional surface for engagement with the wedge-like end of the cam member.

Fig. 17 shows an attachment for varying the effective length of ties 112 or the like. 30 This attachment comprises a block 180 slidably mounted upon the body portion of the tie 102 and provided with an opening 181 adapted to receive a nail or any suitable wedge 184 to lock the block 180 fixed in relation to the tie. The block is provided with a

hook portion 185 adapted to engage the flange of an upright 101.

Fig. 18 illustrates a construction adjoining the inner part of a corner portion of the form. In this embodiment of the invention 70 I-beams 101 at the corner are connected by the wooden elements 190 which correspond to the form boards but may be permanently secured to each other and to filler blocks 193. Upon the latter are secured the angle members 194 which are bolted to the I-beams by fastening elements 195 as shown. Thus the uprights and connecting elements at the corner of the assembly form one unit.

It is evident that the corner assemblies shown in Figs. 7 and 8 may be constructed in a manner similar to that described with reference to the typical wall section. With the form of the invention shown in Fig. 8 the members 72 may be secured to the I-members 1 before the same are brought to their vertical position so that in effect the pair of I-members at the outer corner of the building constitute one part of the assembly.

Each form board may be positioned with its ends within the channels of the uprights by locating one of its ends in loose engagement with one channel and then moving its opposite end into engagement with the other channel, the locking means in their inoperative positions and the shapes and relative dimensions of the various parts readily permitting this operation, or the reverse operation of removing the board from the uprights. The length of each form board is less than the distance between the right portion of one upright and the flanged end of the adjoining upright, as shown for example in Fig. 8. The members 53 are brought into wedging engagement with the flanges of the I-members in order to hold the form boards firmly in position; in this connection the normal inclination of the inner face of the I-beam flange cooperates with the bevel upon the end of the cam to effect the wedging engagement between these elements which is necessary to hold the parts in place. It is often preferable to pour concrete into the lower part of the form and to permit the same to set initially, then to loosen the fastenings 53 when the concrete is still "green", thereby permitting easy stripping of the form board from the concrete, and to lift the form board to a position above its original position where it may be used again after the lower portion has taken its preliminary set and before it has entirely set, thus preventing the movement of the heavier aggregate to the bottom of the wall as is likely to occur when the entire wall is poured at one time.

The provision of the openings 12 in members 7 permits the extremely easy and accurate centering and alignment of the form so that the poured wall may be accurately located in desired position upon the foundation,

ground, or other suitable base. When the concrete has set sufficiently the form may be disassembled, the bolts 10 being removed from the nuts 11 to leave the members 7 embedded within the cementitious material with their ends 8 flush with the faces of the wall.

I claim:

1. A concrete form comprising pairs of uprights, uprights of each pair being disposed at opposite sides of a space to be filled by pouring, form boards extending between the uprights, vertically extending channels in the uprights receiving the form boards, locking means engaging the channel walls to hold the boards in place, transverse ties securing each pair of uprights to each other and comprising parts abutting the outer surfaces of the uprights, and swinging cam-like members for holding the uprights outwardly against said parts of the transverse ties.

2. A concrete form comprising uprights of I-section arranged at either side of the space to be filled by pouring, form boards extending between the uprights, locking means engaging the uprights to hold the boards in place, transverse ties securing opposite uprights to each other and comprising members extending about the outer surfaces of the uprights, and swinging cam-like members for holding the uprights outwardly against the transverse ties.

3. A self-supporting concrete form comprising uprights, form boards extending between the uprights, vertically extending channels in the uprights receiving the form boards and locking means engaging the channel walls to hold the boards in place, transverse ties securing uprights to each other and comprising members extending about the outer surfaces of the uprights, and means combined with the transverse ties for engaging longitudinal connections between the uprights, said transverse ties being vertically slidable upon the uprights, and said form boards being vertically slidable in the channels.

4. A concrete form comprising uprights, vertically extending channels in the uprights, form boards adapted to extend between the uprights with their ends located within the channels, locking means upon the boards adapted to engage the channel walls to hold the boards in position, the channel boards and locking means being so arranged that the boards may be disposed with their ends within the channels by fitting one end of each board in loose engagement with one channel and subsequently locating the opposite end of the board in the other channel.

5. A concrete form comprising flanged uprights affording channels at either side of the space to be poured, form boards having their mold faces substantially flush with the mold faces of the uprights and having their ends

engageable in the channels, locking means engaging the outer flanges of the channels, the length of said form boards being less than the distance between the right surface of one channel and the flange edge of the adjoining channel, whereby the boards may be horizontally removed upon release of the locking means.

6. A concrete form comprising uprights, form boards extending between the uprights, vertically extending channels in the uprights receiving the form boards and arranged and proportioned with respect thereto to permit direct removal of the boards in a horizontal direction without necessity of vertical movement and locking means engaging the channel walls to hold the boards in place.

7. A concrete form comprising a plurality of uprights arranged at opposite sides of a space to be filled by pouring, form boards extending between the uprights, said uprights comprising webs extending transversely to the form boards and pairs of oppositely disposed flanges defining a channel which receives the adjacent form board, and movable cams carried by the form boards, a movable cam being adapted to extend into the channels of the upright and being engageable with the inner face of a flange of the upright or forcing the form board against the opposite flange of the upright.

8. A concrete form comprising a plurality of uprights of I section, the flanges of the same having inclined inner faces, form boards extending between the uprights, the end of a form board extending within the channel defined by the flanges of an upright, and a rotatable cam carried by a form board and engageable with the inner inclined face of one of the flanges of the uprights for forcing the form board against the opposite flange of the upright.

9. A self-supporting concrete form comprising pairs of uprights, the uprights of each pair being arranged at opposite sides of a space to be filled by pouring, form boards retained by the uprights, transverse ties securing opposite uprights to each other and comprising members slidably engaging the opposite outer sides of opposite uprights, cam means for adjustably retaining said transverse ties at desired levels and longitudinal ties connecting adjacent transverse ties, independently of said uprights.

Signed by me at Boston, Massachusetts, this twenty-first day of November, 1927.

ISAAC W. LITCHFIELD.
